UNITED STATES PATENT OFFICE.

HERBERT M. FRIENDLY, OF PORTLAND, OREGON.

TELEPHONE SYSTEM.

Application filed December 21, 1916. Serial No. 138,149.

To all whom it may concern:

Be it known that I, HERBERT M. FRIENDLY, a citizen of the United States, and a resident of Portland, Multnomah County, 5 Oregon, have invented certain new and useful Improvements in Telephone Systems, of which the following is a specification.

My invention relates to what are generally known as full automatic telephone systems, semi-automatic telephone systems and variations of such systems, including manual telephone systems.

An object of my invention is to render more flexible and effective the involved 15 equipments and to enable both central office and outside construction to be conserved to a greater degree than practicable using methods heretofore in practice or known so far as I am aware. Other objects of my invention and the invention itself will be clear 20 from the following description thereof.

In the accompanying drawings:—

Figure 1 is a schematic layout of the elements associated with a subscriber's line in 25 a type of automatic exchange hereinafter referred to, embodying my invention.

Figure 2 is an end view of a branch block of my invention.

Figure 3 is a side view of said branch 30 block.

Figure 4 is a front view of said branch block.

Figure 5 is a second side view of said 35 branch block.

As an illustration of my invention I shall set forth herein a typical system embodying 40 my invention. This invention is primarily a novel organization of well known equipments in a new combination and disposition. By my novel arrangement I gain 45 structural and operative advantages as will hereinafter be discussed.

For the purpose of this illustration I have chosen the well known "two-wire" 50 automatic system of the Strowger type as extensively used and now furnished by the Automatic Electric Company of Chicago, Illinois.

This system of the Automatic Electric 55 Company in its general organization consists of a line-switch unit consisting of a number of individual line-switches; a system of selectors and a connector and connector bank system. The lines first enter and connect to terminals on the main distributing

frame; from these terminals jumpers are run to the terminals of the said line-switches, which said terminals are also provided with lightning or abnormal current protectors. From said line-switches wires 60 are run to the terminals of the corresponding connector bank multiple so that incoming calls are received by the line-switch individual to the respective line calling and this call is then extended via the selector 65 system and trunks to the desired connector bank multiple to which the called subscriber's line is connected.

In order that the various subscribers on any party line that may be called may be 70 signaled selectively, it has been a practice to use as many characters or frequencies of signaling current as there are subscribers on any line, or side of any line to be signaled upon. The bells, or other signal devices at the subscribers' premises are arranged to be responsive only to certain pre-arranged character of currents. The connectors having access to the various connector banks are arranged to project the 80 different characters of signaling current prearranged. Thus, 100 subscribers' outgoing lines, or other unit number of lines, would be carried through a plurality of multiplied connector banks, and these connector banks would, in turn, be accessible 85 to as many classes of connectors with reference to signaling current characteristics or frequencies as there would be classes of signal devices on the connected subscribers' 90 premises. It has been a practice to designate each class of connectors above as a different hundred; that is, if alternating currents of the frequencies 16, 33, 50 and 66 cycles are used for signaling and that 28 95 connector banks were available for outgoing switching to any said line, there would be, for instance, 7 connectors arranged for impressing each signaling frequency upon that line. Further, to reach these various 100 groups of connectors selectively, the calling subscriber would call a different selector sub-unit. For instance, for calls to 4100-

4199 the calling party would obtain access to a connector impressing 16 cycles; for 105 calls to 4200-4299 the calling party would obtain access to a connector impressing 33 cycles; for calls to 4300-4399 the calling party would obtain access to a connector impressing 50 cycles and for calls to 4400- 110

4499 the calling party would obtain access to a connector impressing 66 cycles. The "privates" of each line, appearing as multiplied at every one of the said 28 connector banks, will cause the line to "test busy" when any connector, regardless of its signaling frequency characteristic, is in connection with it.

I am aware that it has been a practice to bring groups of connector banks associated with the different frequency types of connectors to terminals in the switchboard and there to have provisions for disassociating any lines in any set or sub-unit of connector banks pertaining to any particular set of connectors having access thereto, and further to be able to extend any of these disassociated lines to an information operator, or other operator, who might receive any outgoing call made to the line through any of the connectors. That is, say that we have disassociated line 4127 from the line group 4127-4227-4327-4427 and in turn connected it to the information operator, any party calling for this number would obtain the connector bank corresponding through one of the connectors arranged for impressing 16 cycle signaling current, and the signal would appear at the information switchboard and would not be impressed out upon the line since there has been a disassociation of this connector bank branch from the line at the switchboard.

It is clear from the above that this number 4127 cannot be used for a new subscriber as long as there is any possibility of confusion to the public by it not being aware that the old subscriber corresponding has been discontinued, and it is further clear that there will, therefore, be this number vacancy on the line. If the line be a four-party line as in the case described, the line will now have but three parties connected thereto.

It is also clear from the above that the 4100-4199, 4200-4299, 4300-4399, 4400-4499 are expressly set apart as a connector bank unit, and that the corresponding numbers in each hundred must be associated if in service, since but one terminal common to all corresponding numbers in each hundred appears on the connecting rack where outside lines may be joined through jumpers.

By my novel organization of equipments I arrange the companion connectors of each hundred unit of connector banks with a pre-arranged frequency for signaling. These units are chosen at random throughout the central office and would ordinarily be divided about equally to the various frequencies used in any office where party-line service is given.

I then provide an intermediate distributing block or branch block from which a jumper is run from the line-switch of the

particular outside line concerned and from this block as many jumpers are run as there are subscribers connected to the particular line. For instance, if there are four subscribers on a line, each having a signal device responsive to a particular frequency as hereinbefore mentioned, there will be four jumpers run from the branch block; one extending to a hundred having connectors provided for impressing 16 cycles; one extending to a hundred having connectors provided for impressing 33 cycles; one extending to a hundred having connectors provided for impressing 50 cycles and one extending to a hundred having connectors provided for impressing 66 cycles. Thus the connector bank numbers, or otherwise subscribers' numbers, connected to a particular line may be widely different, and not bear any certain prearranged numerical relation further than such numbers be chosen in connector banks whose connectors will have the desired signaling frequencies. In case any subscriber should be disconnected from the line the corresponding jumper would be disassociated from the branch block of that line and would be connected to the information operator, who would receive any signals destined to that subscriber. A new jumper may then be run from this branch block to any connector bank number that is in a unit having the same frequency as the one disconnected, or that may be vacant on the respective line and the new subscriber with corresponding responsive signal equipment placed upon the line with a telephone number corresponding to the new connector bank number.

It will be thus understood that if two or three subscribers are to be connected on a line and selectively signaled where the central office equipment is provided with four frequencies as described, just the desired frequencies may be chosen. Thus a two-party line may have signals at the subscribers' premises responsive to 16 cycles and 50 cycles respectively. A second two-party line connecting into the same central office may have signals at the subscribers' premises responsive to 33 and 50 cycles respectively, or 16 and 50 cycles respectively, etc.

If a line is an individual one, that is, has but one subscriber connected to same, the signal at such subscriber's premises may be susceptible to any desired signal current consistent with that of the connectors having access to the connector banks in which this particular subscriber's number is found.

Thus it will be observed if a party line subscriber, for instance, desires to be re-classed as an individual line subscriber it is simply a matter of connecting his telephone equipment on a separate line and associating his former connector bank number with the new line. This is particularly advantageous from the fact that it permits the operating

company to obtain party line subscribers at lower rates than would have to be charged for individual service and then leaves the way open to change the class of service at 5 an opportune time without service confusion or undue clerical work. It also permits ready regrouping of subscribers for construction reasons or personal preferences of subscribers without the necessity of number 10 changing.

As a further instance may be mentioned changing from four-party to two party classification, or vice versa. This involves only a reclassification on the outside line, 15 with due regard to connecting but one of any character of signal device, or a number denoting but one of any character, on any line, and then effecting a corresponding grouping of the connector bank numbers in 20 the central office equipment.

Each line group is assigned a line switch for use to incoming calls; lines being usually arranged for two-way service, but the latter is not essential to gain the advantages of 25 my new arrangement. Line switches not being permanently associated with the connector banks allows the utmost flexibility and obviates the necessity of holding idle line switch equipment if a connector bank 30 number must be held idle; due perhaps to a discontinuation of service and in order to avoid confusion by reassignment of connector bank number before the issue of a new directory eliminating former listing.

35 In addition to the above advantage due to my improved arrangement, it is thereby possible to intermix individual and party line subscribers' numbers of the various classes in the connector banks or outgoing 40 units so advantage of the outgoing traffic divergency between the various classes in the connector banks or outgoing units may be taken in each separate unit. That is, individual and party line subscribers of various 45 classes with their different load characteristics may be intermixed in the separate connector bank units as well as in the separate line switch units. Thus, the arrangement conduces to the obtainment of the same 50 "load factor" and characteristic load in each connector bank unit as obtains in the collective units, within close approximation. It in effect obtains the same advantages sought in enlarging connector bank groups.

55 Obviously, with a certain traffic the minimum number of connectors will be required where the probable traffic in each connector bank group will be the same for all periods as against any arrangement wherein the 60 traffic does not tend to be spread uniformly.

My new arrangement has other incidental advantages, such as making the traffic through the selector system more uniform and not subject to such variations into certain selector numerical order groups as here-

tofore found, due to the intermixing within more closely defined limits of the classes of service. My new arrangement thus permits fewer selector switches to be used consistent with the gross traffic than heretofore possible since the tendency will be to spread the maximum traffic in all classes over all selectors and connectors of all the different numerical orders and groups in place of only to certain decades and connector groups containing solid subscriber classes having certain and peculiar load characteristics. As for instance, business subscribers of certain classes may use the telephone during the mid morning hours, while certain classes of users 70 of residence telephones may use the service 75 after working hours, etc.

Outside construction will be conserved due to the fact that it will be possible to conveniently group subscribers on the outside 80 into classes on the same line regardless of the telephone numbers assigned to them, and then conform to such outside grouping as described, on the inside, bearing in mind only that two numbers indicating the same 85 ringing frequency will not be placed upon the same circuit.

There is also the new advantage of being able to change the class or rating of a subscriber by separating such telephone from 90 others and associating with still others or individually, and all without changing the subscribers' numbers. Changing of telephone numbers is inconvenient to the subscribers and to the operating company. It 95 forces the operating company to keep the released number under observation until such time as it may be reassigned without probability of confusion. It incidentally forces into idleness equipment for which no 100 revenue can be obtained. A displacing subscriber on the outside line would obtain outgoing service through the regular line switch of that line. A jumper run to the newly assigned connector bank number also 105 being the new subscriber's number, affords 110 outgoing access to the line from other subscribers in the exchange.

One of the objects attained by my invention is the arrangement permitting widely 115 different numerically irrelevant numbers to be assigned to the subscribers on a party line, and further, to change at once such combination without service confusion.

The following describes in detail the organization of my invention as applied only to the system before referred to:

In Fig. 1, 1 and 2 are line wires entering the office, ending upon distributing frame terminals 3 and 4. From the latter terminals jumpers are run to the distributing frame terminals 7 and 8, between which are connected protectors 9 and 10. From terminals 7 and 8 cable wires 11 and 12 extend to other distributing frame terminals 14 and 125 130

15. From terminals 13, 14 and 15 wires extend to a line switch or to a first selector over wires 16, 17 and 18. The foregoing in this paragraph also applies to usual practice. By my new organization I introduce branch blocks or the equivalent. A group of terminals of one such block are designated by 22, 23 and 24 respectively.

The sets of three terminals 37 to 69 inclusive are the terminals of lines and privates of said lines no two of which are in the same unit of connector banks. The said connector bank terminals are located on blocks of usual types and these blocks are on the 15 distributing frame, accessible by jumper wire from branch block 22, 23 and 24.

Where 100 lines is the unit connector bank group the above referred to sets of terminals would comprise one line only of such 20 unit. The schematic drawing, therefore, represents one line of each 11 connector bank units or groups.

The heavy short lines on the lighter lines leading toward the right from the said terminals 37 to 69 inclusive represent connector bank contacts. It is to be assumed that connectors have access to these connector bank contacts.

It will also be assumed that 37, 38 and 39 30 are the terminals of 1137; that 40, 41 and 42 are the terminals of 1763; that 43, 44 and 45 are the terminals of line 1929; that 46, 47 and 48 are the terminals of 2172; that 49, 50 and 51 are the terminals of 2320; that 52, 53 35 and 54 are the terminals of 2511; that 55, 56 and 57 are the terminals of line 2722; that 58, 59 and 60 are the terminals of 3921; that 61, 62 and 63 are the terminals of line 4858; that 64, 65 and 66 are the terminals of 5773; 40 that 67, 68 and 69 are the terminals of 6583. Further that the connectors having access to 45 the connector banks in which are the above numbers are designed to impress signalling frequencies as follows:—

1100-1199, 16 cycles; 1700-1799, 33 cycles;

1900-1999, 33 cycles; 2100-2199, 50 cycles;

2300-2399, 66 cycles; 2500-2599, 50 cycles;

2300-2399, 66 cycles; 3900-3999, 66 cycles;

4800-4899, 16 cycles; 5700-5799, 50 cycles.

50 I am thus enabled to assemble a party line group 1137, 1763, 3921 and 5773. The four 55 said numbers appear in four respective connector bank groups wherein the groups of connectors accessible to the said bank groups 60 impress a specific signaling current frequency. For example, the groups of connectors accessible to the four bank groups corresponding to the said party line group 1137, 1763, 3921 and 5773 project 16 cycle, 66 cycle, 66 cycle and 50 cycle, respectively. On the outside line wires, 1 and 2, are connected the subscribers' signal devices, the 65 characteristics of each said signal device corresponding to the signaling frequency of the connectors having access to the correspond-

ing bank branch leading from branch block 22, 23 and 24.

It will be noted the private terminals 37, 40, 58, 64, 22 and 13 are tied together and connect to a line switch private over wire 70 16. Line switches, selector switches and connector switches have been omitted from the drawings since their functions and relation are well known.

It is obvious that by disconnecting jumper 75 wires 34, 35 and 36, for instance, terminals 64, 65 and 66 may be jumpered to terminals leading to any special operator who would answer any calls to the corresponding telephone number. Also it is obvious that the 80 said jumper may be transferred to connect from terminals 22, 23 and 24 to 49, 50 and 51 and a displacing subscriber on the outside line given a signal device responsive to the 85 same character of currents as the signal device of the displaced subscriber but with a new telephone number, 2320. Likewise, all jumpers may be removed from branch block 22, 23 and 24 and each said jumper run to 90 separate line switch terminals, as 13, 14 and 15. Thus connected, the service to each said subscriber would be "individual". However, signal devices at the subscribers' stations will have to correspond to the signaling 95 frequencies of the connectors in access to the respective connector banks in which are found the subscribers' numbers.

From the foregoing it is apparent that any desired system of number assigning 100 may be used, intermixing classes in the line switch units and in the connector banks and that the subscriber's number need not be indicative of its class to those not specifically posted.

It is not necessary that all the said connector bank groups be a part of the same "office" or major group. As for instance, if the system is what is known as a "100,000 system" in which subscribers' numbers are made up of five digits, the first digit denoting the "10,000 group." With my new arrangement, the parties on a party line may have numbers in different "10,000 groups" by carrying out the plan of jumping outlined, however, bearing in mind the frequency characteristics of the different connector groups. This would occur if any one "office" had two or more "10,000 groups", or were contiguous offices.

The terminal block of my invention for use herewith shown in Figs. 2, 3, 4 and 5 appears like a well known form with the exception that the three sets of attaching lugs are metallically tied together in groups of fours, by ties 22^t, 23^t and 24^t. For instance, terminal 24 has four lugs, 24^a, 24^b, 24^c and 24^d for branching to connector bank terminals. 22, 23 and 24 have lugs 22^e, 23^e and 24^e for receiving jumpers from line switch terminals 13, 14 and 15 respectively. Mem- 130

bers B, C, D and E are insulating, dividing and clamping strips the use of which is well known.

5 Jumpers may be run from the branch block lugs indiscriminately, but I prefer to designate the lugs as regards frequencies. Therefore, jumpers from lugs 22^a, 23^a and 24^a extend to 16 cycle connector banks; jumpers from lugs 22^b, 23^b and 24^b extend to 33 cycle connector banks; jumpers from lugs 22^c, 23^c and 24^c extend to 50 cycle connector banks; jumpers from lugs 22^d, 23^d and 24^d extend to 66 cycle connector banks.

10 Only two sets of terminals as above are shown. The blocks carrying these lugs may carry any number of sets of lugs.

15 So it is possible by virtue of my block arrangement forming a part of my invention, for those employed about the central office equipments to readily note how many subscribers' connector bank multiples, indicating the number of lines connected, run to each branch block and corresponding line switch and outside line. Further, to know what frequencies of signal current is applied if all are not connected. Further, it permits ready placing of jumpers.

20 It is possible to combine terminals 13, 14 and 15 with 22, 23 and 24. That is, bring wires 11 and 12 to terminals 23 and 24 respectively and wires 16, 17 and 18 directly to terminals 22, 23 and 24 respectively, omitting terminals 13, 14 and 15.

25 Signaling currents of four frequencies have been hereinbefore mentioned. It is obviously feasible to employ ground seeking currents of one or more frequencies and connect subscribers' signals to correspond. It is also obviously feasible to connect a greater number of subscribers and consistent connector bank multiple numbers to any line using additional signaling current types or introducing signaling current intermittently to form signaling codes. Further, it is possible to omit the line switch without affecting outgoing traffic.

30 The foregoing descriptions and the mention of the possible modifications are by way of illustration only and are not intended to be exhaustive. My invention is, therefore, capable of wide modification and detailed changing. It may be employed in part only or as an amplification without departing from its scope.

35 Having thus described my invention, what I claim is:—

40 1. In a telephone system, a plurality of subscribers' signal devices selectively responsive; a line extending to a central exchange and there branching to connector bank numbers having no numerical relationship, said connector bank numbers being accessible to connectors designed to impress currents of characters adapted to selectively actuate said signal devices.

45 2. In a telephone system, a plurality of subscribers' signal devices selectively responsive on a line extending to a central exchange; connector banks accessible to connectors designed to impress currents of characters adapted to selectively actuate said signal devices; a cross connecting rack upon which the terminals of the said connector banks terminate; means for connecting together in multiple relation the numbers of the said connector banks conforming with the calling numbers assigned to said signal devices.

50 3. In a telephone system, a plurality of connector bank units, each unit accessible by connectors adapted to project different characters of signaling currents; a cross connecting rack upon which independently terminate the said connector bank units; line terminals on said rack accessible by jumpers to a plurality of component elements of said connector bank units.

55 4. In a telephone system, a plurality of connector bank units, each unit accessible by connectors adapted to project different characters of signaling currents with respect to the other units; a cross connecting rack upon which independently terminate the said connector bank units; line terminals on said rack accessible by jumpers to the component elements of said connector bank units.

60 5. In a telephone system, a connector bank unit having accessible thereto connectors adapted to project a predetermined character of signaling current; a cross connecting rack upon which said unit terminates accessible by jumper to line terminals; jumper connections from said unit's elements to lines having a single signal device responsive to said signal current and jumper wires from other said unit's elements to lines having a plurality of signaling devices each responsive to predetermined current characters, one or more of which signal devices are responsive to the character of signaling current projected by the said accessible connector.

65 6. In a telephone system, a plurality of connector bank units, each unit having accessible thereto connectors adapted to project different characters of signaling current; a cross connecting rack upon which independently terminate the said connector bank units; line terminals on said rack accessible by jumper in multiple relation to a plurality of component elements of said connector bank units and also accessible by temporary jumper in independent relation to other component elements of said connector bank units.

70 7. In a telephone system, a line extending from a plurality of differently responsive signal devices to component elements of connector bank units having no inherent relationship, said banks accessible by connec-

tors which impress characters of signaling current which will selectively actuate the said signal devices.

8. In a telephone system, a plurality of 5 subscribers' signal devices selectively responsive; a line extending to a central exchange and there branching to connector bank numbers through jumpers, said numbers having no permanent structural relationship; connectors designed to impress 10 currents of characters adapted to selectively actuate said signal devices.

9. In a telephone system, a plurality of 15 connector bank units, each unit accessible by connectors adapted to project a different predetermined character of signaling current; line switches, a cross connecting rack upon which independently terminate the 20 said connector bank units and the said line switches; line terminals; means for jumpering 25 said connector, line switch, and line terminals, and a line extending from said line terminals upon which are connected signal devices selectively responsive to said signaling current.

10. In a telephone system, a plurality of connector bank units each having accessible thereto connectors adapted to project a predetermined character of signaling current; 30 a cross connecting rack upon which said units independently terminate accessible by jumper to line terminals, jumper connections from said units' elements to terminals of lines having a single signal device responsive to a character of said signal current and jumper wires from other said units' 35 elements in multiple relation to terminals of lines having a plurality of signal devices each responsive to predetermined current 40 characters corresponding to characters of signaling currents said connectors are adapted to project.

11. In a telephone system, a plurality of connector bank units, each unit accessible 45 by connectors adapted to project different characters of signaling currents; a cross connecting rack upon which independently terminate the said connector bank units; line terminals on said rack accessible by 50 jumpers to the component elements of said connector bank units; a line extending from said line terminals on to which are connected subscribers' signal devices selectively responsive to said signaling current characters.

12. In an automatic telephone system having 55 subscriber lines of a plurality of classes as individual and party lines, a plurality of connector bank units corresponding to each of a plurality of characters of signaling current, selectively responsive signal devices for interchangeable connection to the subscriber lines, signaling currents having characteristics corresponding to the signal devices, a cross connecting frame, terminals

on said frame for the lines and for each of the connector bank units; the method of intermixing subscribers' lines of the various classes in each of the connector bank units so as to equalize the load characteristics 70 thereof, consisting of interconnecting connector bank terminals at the frame corresponding to the said units, with line terminals of the frame, with approximately the same proportion of each class of subscribers' 75 lines connected into each said unit.

13. In a telephone system, a telephone line; line terminals therefor, a plurality of bells on said line; a plurality of connector banks at the exchange, each accessible to 80 connectors which are adapted to apply selective ringing current to said line to operate any particular one of said bells; a plurality of second sets of line terminals each one of which is associated with the said connector banks; means to interconnect said first set and said second sets of terminals; a second like line and means to disassociate any of said second sets of terminals from said first set and to associate said second set to the 85 first set of the second telephone line.

14. In an automatic telephone system, a party line incoming to an exchange, a calling branch for said line terminating in an automatic switch, a plurality of called branches for said line accessible, respectively, to a plurality of connector groups, means in the connectors of the several groups for performing different characteristic signaling operations corresponding to 95 the different substations on said party line, a permanent connection between the said line and the said calling branch, and a distributing frame upon which the said line and the said called branches are temporarily connected by means of jumpers.

15. In an automatic telephone system, a plurality of party lines each terminating in an automatic switch, said switches being operable to extend outgoing calls from said lines, means for distributing incoming calls among the subscribers on said lines comprising groups of automatic connector switches and a series of called line 110 branches accessible to each group, and an intermediate distributing frame whereat each party line may be connected at will with any desired plurality of said branches.

16. In an automatic telephone system, main and intermediate distributing frames, 115 lines incoming from the main frame and terminating on the intermediate frame, permanently connected calling branches for said lines extending from the latter point to automatic switches, groups of automatic connector switches, a plurality of called branches accessible to each connector group 120 and terminating on said intermediate frame, a series of junctions on said intermediate frame, and jumpers connecting each junction 125 130

tion with one of said lines and with a plurality of said called branches.

17. In an automatic telephone system, an intermediate distributing frame, incoming party lines terminating on said frame, permanently connected calling branches for said lines extending from said frame to automatic switches, means for selectively signaling said lines comprising groups of connector switches, the connectors of the several groups being adapted to perform different characteristic signaling operations, a plurality of called branches accessible to each connector group and terminating on said intermediate frame, a series of junctions on said frame, and jumpers connecting each junction with one of said party lines and with a called branch coming from each of said connector groups.

18. In an automatic telephone system, a subscriber's line incoming to the exchange, a calling branch for said line terminating in an automatic switch, a plurality of branches individual to said line over any one of which said line may be called, and a distributing frame on which the said line and its several branches are interconnected by interchangeable jumpers.

19. In an automatic telephone system, a party line incoming to an exchange, a calling branch for said line terminating in an automatic switch, a plurality of called branches for said line accessible, respectively, to a plurality of connector groups, means in the connectors of the several groups for performing different characteristic signaling operations corresponding to the different substations on said party line, and a distributing frame on which the said line and its branches are interconnected by interchangeable jumpers.

20. In an automatic telephone system, a subscriber's line incoming to the exchange, a calling branch for said line terminating in an automatic switch, a plurality of called line branches for said line, a permanent connection between the said line and the said calling branch, and a distributing frame upon which the said line and the said called branches are temporarily connected by means of jumpers.

21. In an automatic telephone system, a plurality of subscriber lines, a cross connecting frame, cross connecting jumpers, connector bank branches, a plurality of selectively responsive substation signal devices on the subscriber lines, the subscriber lines and connector branches respectively terminating on sets of terminals of the connecting frame, connectors specific to the respective connector branches for projecting signaling current over corresponding branches having characters of signaling current specific to the branches and also the said signal devices on the subscriber lines, means for interchang-

ing the said signal devices among the subscriber lines, and means for interchangeably connecting the said branches among the subscriber lines through said jumpers attached to respective said terminal sets in correspondence with the interchanged signal devices so that depending upon what branch is employed in completing a connection from a said connector to a subscriber line will determine what said signal device on the connected subscriber line will be effectively operated.

22. In an automatic telephone system, a plurality of subscriber lines, a cross connecting frame, cross connecting jumpers, connector bank branches, selectively responsive substation signal devices on the subscriber lines, the subscriber lines and connector branches respectively terminating on sets of terminals of the connecting frame, connectors specific to the respective connector bank branches and to the signal devices, and means for interchangeably connecting the said branches among the subscriber lines through said jumpers attached to respective said terminal sets to conform to the connected said signal devices so that depending upon what branch is employed in completing a connection from a said connector to a subscriber line will determine what said signal device will be effectively operated.

23. In an automatic telephone system, a plurality of subscriber lines, a cross connecting frame, connector bank branches, jumpers, switch mechanism for extending connections to any said connector bank branch, signaling current of different characters, but one said character for application over the respective branches, selectively responsive substation signal devices, the said branches and subscriber lines terminating in sets of respective terminals on the connecting frame, means for interchangeably connecting a plurality of said signal devices along the subscriber lines, means for interchangeably connecting as many corresponding connector bank branches to the subscriber lines as there are connected signal devices along the subscriber lines, the branches being interchangeably connected over said jumpers attached multiply to the subscriber line set of terminals and individually to respective sets of connector bank branch terminals, and means whereby effecting a connection from the switch mechanism over a said jumper to a subscriber line will cause only a specific said signal device on the subscriber line to be effectively operated in selective correspondence with the jumper forming a link of the connection.

24. In an automatic telephone system, a plurality of subscriber lines of a plurality of classes respectively, the said classes being characterized by certain traffic characteristics respectively, a cross connecting frame, cross connecting jumpers, a plurality of groups

of connector bank branches, the said groups terminating in a plurality of connector bank units respectively, a group of connectors for each said unit, the subscriber lines and connector bank branches respectively terminating in a set of terminals on the cross connecting frame, means for interchangeably uniting the respective subscriber lines with any variable number of connector bank branches by correspondingly interconnecting the said terminals by one or more said jumpers, a specific corresponding signal device interchangeably connected on said subscriber lines for each connector bank branch connected by jumper to a concerned subscriber line, sources of signaling current the application of which is controlled by the connectors for operating the said signal devices selectively with relation to other signal devices connected on the same line, the signaling current applied being dependent upon what connector bank branch is seized by a connector in linking the connection, and means including the said frame and jumpers whereby the connector bank branches of the subscriber lines of the various said classes may be distributed among the different said units so each said unit will contain approximately the same proportion of connected connector bank branches belonging to each class of subscriber lines, whereby at all times of traffic an approximately equal though possibly variable number of connectors will be engaged in each unit capacity.

25. In an automatic telephone system, a plurality of subscriber lines of a plurality of classes respectively, the said classes being characterized by certain traffic characteristics respectively, a cross connecting frame, cross connecting jumpers, a plurality of groups of connector bank branches, the said groups terminating in a plurality of connector bank units respectively, a group of connectors for each said unit, the subscriber lines and connector bank branches respectively terminating in a set of terminals on the cross connecting frame, means for interchangeably uniting the respective subscriber lines with any variable number of connector bank branches by correspondingly interconnecting the said terminals by one or more said jumpers, a specific corresponding signal device interchangeably connected on said subscriber lines for each connector bank branch connected by jumper to a concerned subscriber line, sources of signaling current the application of which is controlled by the connectors for operating the said signal devices selectively with relation to other signal devices connected on the same line, the signaling current applied being dependent upon what connector group contains the connector linking the connection, and means including the said frame and jumpers whereby the connector bank branches of the

subscriber lines of the various said classes may be distributed among different said units so each said unit will contain approximately the same proportion of connected connector bank branches belonging to each class of subscriber lines, whereby at all times of traffic an approximately equal though possibly variable number of connectors will be engaged in each unit capacity.

26. In an automatic telephone system, a plurality of subscriber lines, a plurality of attendants' lines and signal devices thereon, a cross connecting frame, cross connecting jumpers, called branches, a plurality of selectively responsive substation signal devices on the respective subscriber lines, the subscriber lines, the attendants' lines and called branches respectively terminating on sets of terminals of the connecting frame, switch mechanism for projecting signaling current over the called branches wherein the character of current projected will be specific to the branch connected with, the signal device of the attendants' line being responsive to signaling current, means for interchangeably connecting said called branches with respect to the respective subscriber lines through the said jumpers attaching between corresponding said terminal sets so that depending upon what said branch is employed in completing a connection from the switch mechanism to the subscriber line will depend what said substation device on the connected subscriber line will be effectively operated, and means for disconnecting any said jumper from one of said plurality of subscriber line terminal sets and then alternatively connecting it to the said terminal set of a said attendants' line whereby all calls to the branch connected by jumper with the attendants' line will cause the signal device on the connected attendants' line to effectively operate to indicate that a call has been directed to the subscriber line substation corresponding to the jumper disconnected from the subscriber line, and means for substituting a selectively responsive substation signal device and jumper branched to a called branch of corresponding character to restore the previously connected capacity of the subscriber line.

27. In an automatic telephone system, a plurality of subscriber lines, a cross connecting frame, connector bank branches, calling line branches leading to corresponding line switches, jumpers, selectively responsive substation signal devices on the subscriber lines, switch mechanism, the subscriber lines and the said calling line branches and connector branches respectively terminating on a set of terminals of the connecting frame, each of the terminals of the sets of terminals for the calling line branches being a gang terminal, a said jumper for connecting the subscriber line

- terminals to the calling line branch terminals respectively, other said jumpers branched from specific ones of each of the said gang sets to respective connector bank branches 5 in numerical correspondence with the connected substation signal devices as designated, means including the switch mechanism for connecting to the respective said connector bank branches to effectively operate 10 only one of said signal devices in correspondence with the branch connected with, whereby attaching the jumpers leading to the connector bank branches on respective sets of terminals of the respective said gangs 15 the specific signal device effectively operative over each of the jumpers will be identified by the respective sets of terminals of the gang to which the respective jumpers connect. 20 28. In an automatic telephone system, a plurality of subscriber lines of a plurality of classes respectively, a cross connecting frame, a plurality of called branches terminating in a plurality of connector bank 25 units respectively, a plurality of calling branches terminating in a plurality of line switch units respectively, the subscriber lines, called branches and calling branches respectively terminating on sets of terminals 30 on the connecting frame, means on the said frame for interchangeably uniting a subscriber line with a called branch and a calling branch, means on the said frame for interchangeably uniting a subscriber line 35 with a calling branch and a variable plurality of called branches, signal devices on the said lines in correspondence with the called branch or branches thereof selectively responsive to calls over corresponding said 40 branches, and means including the said frame for distributing the branches by which approximately the same relative number of line switches of each line switch unit and approximately the same relative number of 45 called branches belonging to each class of subscriber line will appear connected in the individual line switch units and the individual connector bank units as appear collectively in all the units respectively, whereby to conduce towards relatively uniform traffic at all times from the line switch units and to the connector bank units, respectively. 50 29. In an automatic telephone system, a plurality of subscriber lines of a plurality of classes respectively, a cross connecting frame, cross connecting jumpers, a plurality of called branches terminating in a plurality of connector bank units respectively, the subscriber lines and the called branches respectively terminating in sets of terminals on the connecting frame, means for uniting a subscriber line with a single called branch, means for uniting subscriber lines with a variable plurality of called branches 55 respectively, the said unitings being effected by attaching said jumpers from said called branches to the respective terminals of the said lines to be united, signal devices on the said lines in correspondence with the called branch or branches thereof selectively responsive to calls over corresponding said branches, and means including the said frame and jumpers for distributing the called branches by which approximately the same relative number of called branches belonging to each class of subscriber lines will appear connected in the individual connector bank units as appear collectively in all the connector bank units. 60 30. In an automatic telephone system, a plurality of subscriber lines of a plurality of classes respectively, a cross connecting frame, cross connecting jumpers, a plurality of called branches terminating in a plurality of connector bank units respectively, the subscriber lines and the called branches respectively terminating in sets of terminals on the connecting frame, means for uniting a subscriber line with a single called branch, means for uniting subscriber lines with a variable plurality of called branches respectively, the said unitings being effected by attaching said jumpers from said called branches to the respective terminals of the said lines to be united, and means including the said frame and jumpers for distributing the called branches by which approximately the same relative number of called branches belonging to each class of subscriber lines will appear connected in the individual connector bank units as appear collectively in all the connector bank units. 65 31. In an automatic telephone system, a plurality of subscriber lines of a plurality of classes, selectively responsive signaling devices for interchangeable connection on the said lines, the said signaling devices corresponding to substations, a cross connecting frame, a plurality of connector bank units, means on said frame for interchangeably extending one or more branches to each said lines from a specific bank position or positions of one or more said connector bank units respectively, each connected said branch and bank position specifically corresponding to a said substation, and means including the said frame and jumpers for distributing the branches to the units whereby each said unit will terminate approximately the same proportion of connected said branches relating to each said class of subscriber lines as are connected into all the units collectively, whereby to conduce toward making traffic percentage coincidentally uniform in all the said individual units. 70 32. In an automatic telephone system, a plurality of subscriber lines of a plurality of classes, selectively responsive substation 75 80 85 90 95 100 105 110 115 120 125 130

signaling devices for interchangeable connection on the said lines, a cross connecting frame, a plurality of connector bank units, means on said frame for interchangeably 5 extending one or more branches to each said lines from a specific bank position or positions of one or more said connector bank units respectively, each connected said branch and bank position specifically corresponding to a said substation, but one 10 branch to a specific subscriber line connected from a specific said unit, and means including the said frame for distributing the branches to the units whereby each said unit 15 will terminate approximately the same proportion of connected said branches relating to each said class of subscriber lines as are connected into all the units collectively, whereby to conduce towards making the 20 traffic percentage coincidentally uniform in all the said individual units.

33. In an automatic telephone system, a plurality of subscriber lines of a plurality of classes, selectively responsive substation 25 signaling devices for interchangeable connection on the said lines, a cross connecting frame, a plurality of connector bank units, means on said frame for interchangeably extending one or more branches to each said 30 lines from a specific bank position or positions of one or more said connector bank units respectively, each connected said branch and bank position specifically corresponding to a said substation, but one 35 branch to a specific subscriber line connected from a specific said unit, the unit through which a connection is made to a subscriber line determining what signal device thereon will be selectively operated, and a means including the said frame for distributing the 40 branches to the units whereby each said unit will terminate approximately the same proportion of connected said branches relating to each said class of subscriber lines as 45 are connected into all the units collectively, whereby to conduce towards making traffic percentage coincidentally uniform in all the said individual units.

34. In an automatic telephone system, 50 party lines having a plurality of substation signal devices and individual lines having a single signal device respectively, the signal devices being interchangeable among the said lines to interchange the classes of 55 the changed lines in accordance with the number of signal devices connected on the lines, the signal devices being selectively responsive with respect to any other signal device on its connected line if a party line, 60 a cross connecting frame, a plurality of groups of connector bank branches each group of said branches terminating in a connector bank unit, a unit of connectors for each connector bank unit specific thereto and adapted to specific signaling selection, the

subscriber lines and connector bank branches terminating on the cross connecting frame, jumpers on the cross connecting frame for joining the respective said lines with a single or a plurality of connector bank branches 70 in accordance with the number of signal devices on the line and wherein more than one branch for a specific line will not correspond to connectors of like signaling selection, and means including the said frame 75 and jumpers for distributing the branches among the connector bank units so each unit thereof will contain approximately the same percentage of branches of subscriber lines of the various said classes as are contained in 80 the groups collectively.

35. In an automatic telephone system, party lines having a plurality of substation signal devices and individual lines having a single signal device respectively, the signal devices being interchangeable among the said lines to interchange the classes of the changed lines in accordance with the number of signal devices connected on the lines, the signal devices being selectively responsive with respect to any other signal device on its connected line if a party line, a cross connecting frame, a plurality of groups of connector bank branches each group of 90 said branches terminating in a connector bank unit, a unit of connectors for each connector bank unit specific thereto and adapted to specific signaling selection, the subscriber lines and connector bank branches terminating on the cross connecting frame, each said signaling device being permanently 95 companion to a specific connector bank branch, jumpers on the cross connecting frame for joining the respective said lines with a single or a plurality of connector bank branches in accordance with the number of signal devices on the line and wherein more than one branch for specific lines 100 will not correspond to connectors of a like signaling selection, and means including said frame and jumpers for distributing the branches among the connector bank units so each unit thereof will contain approximately the same percentage of branches of subscriber lines of the various said classes as are 105 contained in the groups collectively.

36. In an automatic telephone system, a plurality of subscriber lines, a cross connecting frame, jumpers, a plurality of connector branch groups and specific groups of connectors therefor respectively, a plurality of selectively responsive substation signal devices on the subscriber lines, a said branch companion to each said signal device, the connectors of the respective groups containing the branches adapted to selectively operate the corresponding signal devices, and means including the jumpers for at will interchanging the signal devices and the corresponding jumpers among the lines without 115 120 125 130

disabling the selective operation of the respective signal devices from the connectors related to the companion connector branches.

37. In an automatic telephone system having subscriber lines of a plurality of classes as individual and party lines, a plurality of connector bank units, selectively responsive signal devices for interchangeable connection to the subscriber lines, signaling currents having characteristics corresponding to the signal devices, a cross connecting frame, terminals on said frame for the lines and for each of the connector bank units; the method of intermixing subscribers' lines

of the various classes in each of the connector bank units so as to equalize the load characteristics thereof, consisting of interconnecting connector bank terminals at the frame corresponding to the said units, with line terminals of the frame, with approximately the same proportion of each class of subscribers' lines connected into each said unit. 15

Signed by me at Indianapolis, county of Marion, and State of Indiana, this 18th day 20 of December, 1916. 25

HERBERT M. FRIENDLY.
